UNITED STATES PATENT OFFICE.

ERNST F. W. ALEXANDERSON, OF SCHENECTADY, NEW YORK, ASSIGNOR TO GENERAL ELECTRIC COMPANY, A CORPORATION OF NEW YORK.

BOILER AND HEATING ARRANGEMENT THEREFOR.

1,174,375.

Specification of Letters Patent. Patented Mar. 7, 1916.

Application filed November 11, 1913. Serial No. 800,299.

To all whom it may concern:

Be it known that I, ERNST F. W. ALEXANDERSON, a citizen of the United States, residing at Schenectady, in the county of Schenectady, State of New York, have invented certain new and useful Improvements in Boilers and Heating Arrangement Therefor, of which the following is a specification.

10 My invention relates to "boilers and heating arrangement therefor" for converting liquids into vapor and is more particularly designed as a mercury boiler, although not limited to such use.

15 Boilers of this type consist broadly of a plurality of liquid containing elements opening into a suitable vapor chamber and arranged to be heated by a source of heat as a fire box. Each of these elements in a way 20 constitutes a small individual boiler. These elements are arranged to extend from a point over the fire box to a point well removed therefrom and are heated by heat, part of which is imparted thereto by radiation from the fire itself, and the rest by the 25 hot gases of combustion. With such an arrangement it is clear that those portions located directly over the fire box would ordinarily be subjected to the greater heat, while 30 those portions more remote therefrom would receive less heat.

The object of the present invention is to design a boiler wherein each liquid containing element will receive substantially the 35 same amount of heat.

In carrying out my invention I so arrange my boiler that those portions nearest the fire box receive a greater amount of heat by direct radiation and a lesser amount from the hot gases, while those portions arranged 40 more remote receive proportionately less heat by direct radiation and more from the hot gases. I also so arrange my boiler that, with the fire box emitting any given amount 45 of heat, the correct amounts are given up by radiation and retained by the gases for producing equal heating among the elements.

50 Referring to the accompanying drawing wherein I have illustrated certain forms of my invention, Figure 1 is a side elevation showing my boiler in connection with a suitable furnace; Fig. 2 is a partial sectional plan view taken on line $a-a$, Fig. 1; and 55 Fig. 3 is a detail of a modification.

Referring to the drawing, 3 is the housing of a furnace which may be constructed of suitable material as fire brick and within which is arranged a fire box 4 and my improved boiler 5. The furnace is provided with suitable doors 6 and 7 arranged respectively above and below the fire box and with an outlet 8 for the escape of the products of combustion. The boiler as here illustrated is shown as comprising a plurality of depending tubes 9, the upper ends of which communicate with a suitable vapor chamber 10 from which the vapor may be conducted by the outlet 11. The material to be vaporized is supplied to the boiler through the inlet 12. The lower ends of these depending tubes are attached to a dividing and directing wall 13 of heat conducting material, which wall may be made up of a single solid piece of material, or of a plurality of blocks as shown at 14, which blocks may be separate or may be joined together in any desired or approved manner. This wall 13 is constructed of such material and so designed with relation to the fire box as to impart to the depending tubes 9 the desired amount of heat by radiation, the remainder of the available heat being retained by the gases. To this end I may construct the wall 13 of a suitable heat conducting metal or of fire bricks, or partly of some suitable metal and partly of fire bricks, or I may construct the wall in two horizontal sections, the upper section being of some suitable heat conducting metal and the lower section of fire bricks or other suitable material, the fire bricks acting to some extent as a shield to direct radiant heat into the gases. A structure such as last referred to is shown in Fig. 3, wherein 16 and 17 represent the two materials suitably joined together in any known or desired manner. It will be clear, with whatever arrangement of wall structure used, that the wall will be so designed as to thickness and as to relative arrangement with relation to the fire box as to produce the desired heating effect for any particular furnace. In the structures illustrated the wall is shown as having cavities formed therein into which the tubes 9 are fastened as by means of screw-threads. It is to be understood that the specific structure of the tubes 9 as shown is only diagrammatic and by way of example as such tubes may take the form of plain pieces of 105 110

pipe such as illustrated or any other form desired. It is to be further understood that the boiler need not take the specific form illustrated as the tubes 9 need not necessarily be depending and attached at their lower ends to the wall 13, as said tubes might be otherwise arranged and the wall 13 might be used as a dividing and heat transmitting and directing wall only.

10 With the arrangement as described, the heat conducting wall 13 will be heated by direct radiation from the fire, that portion of the wall which is directly over the fire box receiving the most heat from radiation, 15 while the portion farther therefrom will receive proportionately less. This heat will be conducted through the wall 13 to the tubes 9. The hot gases coming from the fire will be deflected along the wall 13 to the back of the furnace where they will then pass around the end of said wall and forward to the exit 8 imparting heat to the tubes 9. It will be clear that these gases being applied to the tubes farthest from the 20 fire box first will give up more heat thereto, the gases gradually cooling as they move forward. By this arrangement those tubes which receive less heat from radiation receive proportionately more from the hot 25 gases whereby a substantially equal heating 30 of all the depending tubes results.

In accordance with the provisions of the patent statutes, I have described the principle of operation of my invention, together 35 with the apparatus which I now consider to represent the best embodiment thereof; but I desire to have it understood that the apparatus shown is only illustrative, and that the invention can be carried out by 40 other means.

What I claim as new and desire to secure by Letters Patent of the United States, is:—

1. The combination with a fire-box and a plurality of fluid containing elements arranged to be heated therefrom, portions of said elements being more remote from said fire-box than other portions thereof, of a wall formed of heat conducting material operatively arranged with relation to the 45 fluid containing elements for distributing the heat due to radiation and directing the hot gases so that the said elements will be uniformly heated.

2. The combination with a fire box and a 50 plurality of fluid containing elements arranged to be heated therefrom, portions of said elements being more remote from said

fire box than other portions thereof, of a dividing wall of heat conducting material in thermal relation to said elements, said 60 wall acting to conduct radiant heat to said elements, and to direct the hot gases so that they are applied to those portions of the elements most remote from the fire box first.

3. A boiler comprising a plurality of depending tubes having their upper ends communicating with a vapor chamber and their lower ends embedded in a wall of heat conducting material.

4. A boiler comprising a plurality of 70 depending tubes having their upper ends communicating with a vapor chamber and their lower ends embedded in a wall of heat conducting material, said wall comprising a plurality of blocks.

5. A boiler comprising a vapor chamber, an inlet and an outlet conduit communicating therewith, a plurality of depending tubes, each opening at one end into said chamber, and a wall of heat conducting 80 material in which the other ends of said tubes are embedded.

6. The combination with a fire box and a plurality of depending tubes arranged to be heated therefrom, some of said tubes 85 being more remote from the fire box than others, of a wall of heat conducting material operatively arranged with relation to the tubes for causing the tubes nearest the fire box to receive a greater amount of heat 90 by direct radiation and a lesser amount from hot gases, and those more remote from the fire box to receive a proportionately less amount from radiation and a greater amount from hot gases, whereby all 95 said tubes will receive substantially equal amounts of heat.

7. The combination with a fire box and a plurality of depending tubes arranged to be heated therefrom, some of said tubes being more remote from said fire box than others, of a dividing wall of heat conductive material separating said tubes from the fire box and in thermal relation to said tubes, said wall acting to conduct radiant 100 heat to said tubes and to direct the hot gases so that they are applied to the tubes most remote from the fire box first.

In witness whereof I have hereunto set my hand this 10th day of November, 1913. 110
ERNST F. W. ALEXANDERSON.
